UNITED STATES PATENT OFFICE.

CORNELIUS J. WILTSIE, OF CHICAGO, ILLINOIS, ASSIGNOR TO WILTSIE MANUFACTURING COMPANY, OF CHICAGO, ILLINOIS, A CORPORATION OF ILLINOIS.

ADJUSTABLE SHADE-FIXTURE.

SPECIFICATION forming part of Letters Patent No. 739,048, dated September 15, 1903.

Application filed November 1, 1901. Serial No. 80,775. (No model.)

To all whom it may concern:

Be it known that I, CORMELIUS J. WILTSIE, a citizen of the United States, and a resident of Chicago, in the county of Cook and State 5 of Illinois, have invented certain new and useful Improvements in Adjustable Shade-Fixtures, of which the following is a full, clear, and exact specification.

The object of my invention is to permit the carriers of adjustable shade-fixtures a limited lateral play without affecting the relative position of the shade-roller bearings to said roller, so that the shade may always be parallel to the window. This I accomplish by 15 the means hereinafter fully described, and as particularly pointed out in the claims.

In the drawings, Figure 1 is a perspective view, on an enlarged scale, of the sliding carriers of an adjustable window-shade, portions 20 of the guide-rods upon which said carriers are mounted, and a shade-roller shown in dotted lines between them and having its central portion broken away. Fig. 2 is a horizontal section of the right-hand carrier, taken 25 on the plane of the center of the bearing-block thereof. Fig. 3 is a similar view showing said bearing-block in a different relative position to said carrier. Fig. 4 is a side elevation of the left-hand carrier and a portion of the 30 guide-rod upon which it is mounted. Fig. 5 is a horizontal transverse section of said left-hand bearing, taken on dotted line 5-5, Fig. 4, looking in the direction indicated by the arrows. Fig. 6 is a front elevation of an adjustable shade-fixture embodying my invention, showing the portion of the brackets to 35 which the upper and lower ends of the guide-rods are secured in section.

In the drawings, A represents the shade- 40 roller, B and C the right and left adjustable sliding carriers having bearings in which the shade-roller is journaled, and D D represents the parallel vertical cylindrical guide-rods on which said carriers have sliding engagement. 45 These guide-rods are placed one on each side of the window-frame and are preferably secured at the top and bottom, so as to have a limited lateral play, substantially as shown in the application for Letters Patent of the 50 United States for curtain-fixtures filed by me

August 12, 1901, Serial No. 71,787, and as illustrated in Fig. 6 of the drawings.

The carrier B is provided at each end with knuckles *a* and *b*, which engage the guide-rods, and is provided with bearing-lugs *c* and *d*, projecting therefrom near its upper and lower end in the same direction, in the alining bearing-apertures of which the pivotal studs *e e'* of the bearing-block *E* are journaled. The bearing-block *E* is preferably of such 55 shape and dimensions that it can turn on the axis of its pivotal studs *e e'* without interfering with the frame of the carrier and is preferably supported by the carrier *B* in such manner as to be removable. I accomplish 60 this removability by making the lower stud *e* shorter than the upper stud *e'* and by making the distance between the bearing-lugs of 65 said carrier such that by raising the bearing-block sufficiently the lower pivotal stud can 70 be lifted out of its bearings and the said block tilted until it is in such position that when moved downward it will clear the lower bearing-lug and permit the withdrawal of its upper pivotal stud from its bearing. To do 75 this, the pivotal studs must either be made tapering toward their extremities or their diameters must be less than that of the bearing-openings in which they are journaled. The carrier is raised or lowered on the guide- 80 rod *D* by means of a cord which is fastened in an opening *f* in a lateral offset *o* of the upper bearing-lug *c*, which is so constructed as not to interfere with the shade-roller during the operation of removing the bearing-block 85 thereof from said carrier. Bearing-block *E* is provided with a transverse opening *n*, the dimensions of which are rectangular, and it is adapted to receive the flattened end portion of the adjacent stationary spring- 90 spindle *r* of the roller *A*, which latter may be loosely seated in said bearing-block, but which I prefer to removably fasten therein by means of a set-screw *j*. The carrier *B* is 95 preferably free to rotate on the guide-rod *D*.

The carrier *C* comprises a body *G* of suitable shape and dimensions, which has knuckles *h h* projecting in the same direction from the upper and lower corner of one vertical edge thereof, and is provided with a tenon *i*, pro- 100

jecting from the same edge at a point mediate said knuckles, which enters a longitudinal groove *g* of the guide-rod *D*, upon which said carrier slides. The body *G* of carrier *C* has a vertically-elongated bearing-opening *k* therein, the upper end of which is made of greater diameter. This construction of the bearing-opening is adopted so as to permit the enlarged head or extremity *s* of the revolving journal *K* of the contiguous end of the roller *A* to be inserted therethrough when the parts of the shade-adjuster are being assembled, so that when the journal is settled in the lower end of said bearing said head *s* will prevent the accidental longitudinal withdrawal or dislodgment of the roller from the carrier. This carrier *C* is raised and lowered on the guide-rod *D* in the same manner as the carrier *B*—namely, by a cord, the lower end of which is fastened in a suitable opening in a lug *t*, projecting from the upper knuckle of the carrier, as shown. Of course it will be understood that the vertical plane intersecting the centers of the bearings of the roller in both carriers *B* and *C* is the same distance from the axial center of their respective guide-rod, and it will also be apparent that regardless of the lateral play of the guide-rods or the rotative movement of the carriers the bearings of the shade-roller (within reasonable limits, of course) will always be at right angles to the axial plane of the said shade-roller and said shade-roller will always be parallel to the plane of the window.

Another important feature of my invention is the ease with which the shade-roller can be inserted and removed from its bearings. In this respect my invention is unique, whether it is desired to remove one or both ends from its bearings.

What I claim as new is—

1. In an adjustable curtain-fixture the combination with parallel guide-rods, carriers longitudinally adjustable on said rods, and a shade-roller the bearing of which in one of said carriers has a rotative movement the axis of which is parallel to the guide-rod.

2. In an adjustable curtain-fixture, the combination with the parallel guide-rods, longitudinally-adjustable carriers one of which has a limited rotative movement about the axis of the guide-rod, and a shade-roller bearing

carried thereby having an axis which is parallel to the guide-rod.

3. In an adjustable curtain-fixture the combination with parallel guide-rods, carriers longitudinally adjustable on said rods, and a shade-roller the bearing of which in one of said carriers has a rotative movement the axis of which is parallel to the guide-rod, and the journal of said shade-roller in the other of said carriers normally retains it against longitudinal displacement.

4. In an adjustable curtain-fixture the combination with parallel guide-rods, longitudinally-adjustable carriers one of which has a limited rotative movement about the axis of the guide-rod, and a shade-roller the bearing of which in said last-mentioned carrier has a rotative movement the axis of which is parallel to the guide-rod, and the journal in the other of said carriers is retained against accidental longitudinal displacement.

5. In an adjustable curtain-fixture the combination with parallel guide-rods, carriers longitudinally adjustable on said rods, a shade-roller, and a removable bearing-block in one of said carriers having a rotative movement the axis of which is parallel to the guide-rod.

6. In an adjustable curtain-fixture the combination with parallel guide-rods, carriers longitudinally adjustable on said rods, a shade-roller, and a bearing-block in one of said carriers having pivotal studs journaled in said carrier whereby said bearing-block has a rotative movement the axis of which is parallel to the guide-rod.

7. In an adjustable curtain-fixture the combination with parallel guide-rods, carriers longitudinally adjustable on said rods, one of which has bearing-lugs projecting therefrom and a removable bearing-block having pivotal studs projecting therefrom in vertical alignment and opposite each other the lower one of which is shorter than the upper, said bearing-block adapted to have a rotative movement the axis of which is parallel to the guide-rod.

CORNELIUS J. WILTSIE.
